UNITED STATES PATENT OFFICE.

JOHN THENSER, OF CARIBOU, MAINE.

HAND-BAG.

1,084,301.

Specification of Letters Patent. Patented Jan. 13, 1914.

Application filed May 25, 1910. Serial No. 563,813.

To all whom it may concern:

Be it known that I, JOHN THENSER, a citizen of the United States, and a resident of Caribou, in the county of Aroostook and State 5 of Maine, have invented certain new and useful Improvements in Hand-Bags, of which the following is a specification, reference being had to the accompanying drawings.

10 This invention relates to improvements in hand bags.

The primary object of my invention is to provide a neat, folding bag for the articles carried by school children.

15 Another object is to provide a bag for small articles carried in the hand, especially arranged to meet the requirements of school children, and comprising a folding bag having a central lunch compartment with outer book, and pencil and pen receptacles, each 20 receptacle being protected by a flap.

Another object is to provide a light, neat inexpensive hand bag so constructed that the same can be folded to form a flat package 25 while not in use.

With these and other objects in view, the present invention consists in the combination and arrangement of parts as will be hereinafter more fully described and finally 30 pointed out in the appended claim, it being further understood, that changes in the specific structure shown and described may be made within the scope of the claim without departing from the spirit of the invention.

35 In the drawings forming a part of this specification and in which like numerals of reference indicate similar parts in the several views: Figure 1 shows a side elevational view of a hand bag embodying my invention, 40 disclosing the pen and pencil holding receptacles. Fig. 2 shows an opposite side view, disclosing the book receiving receptacle. Fig. 3 shows an end view of the bag distended. Fig. 4 shows a section on line 4—4

45 of Fig. 1. Fig. 5 is a section on line 5—5 of Fig. 1, disclosing the bag as folded. Fig. 6 is a section on line 6—6 of Fig. 1, disclosing the bag as distended. Fig. 7 is a detached detail of one of the metal frame members as used 50 in my invention, while Fig. 8 shows a detached detail of one of the clamping frames.

In the accompanying drawings, the numeral 1 designates a main inner bag section made of canvas, leather or other suitable material. This bag section has an accordion 55 plaited bottom 5, so that the bottom portion

of the bag when not in use, can be neatly folded. Secured to this main inner bag section 1, are the two similar end sections 6, which form an integral part of the inner 60 bag section 1, as is shown in Figs. 3 and 6.

In connection with my hand bag, I use a metal frame comprising two similar three sided frame members 13, one of the frame members being shown in detached detail in 65 Fig. 7. At each end, each frame member is provided with an apertured eye 16. Two such members 13, are hingedly connected by means of a suitable pin 15. Each frame member 13 is further provided with a locking button 17, as is usual in constructions of this kind, these buttons being flexed and sprung apart in locking or unlocking, the 70 bag.

The two connected metal frame members 75 13 are connected to the upper ends of the main inner bag section 1, as are the upper ends of the end members 6. The upper ends of the end members 6 however, extend a suitable distance beyond the pivot points 15, 80 as is shown in Fig. 4. This arrangement permits the end members 6 being fully spread out when the metal frame, or the mouth of the bag is opened.

As shown in Figs. 1 and 2, the metal frame 85 members 13 give support to the carrying handles 18.

Secured to one side of the main inner bag section 1, is the outer pliant pocket forming section 2, shown in Fig. 2, the ends of these 90 pliant members 2 being plaited as shown in Fig. 5, as is the bottom 3', as clearly disclosed in Fig. 5, so that this pocket member can be distended to permit the insertion of a slate or the larger books carried by school 95 children.

In Fig. 2, the dotted lines 2 disclose the upper edge of this outer pliant main pocket forming member. A flap 7 is secured to the frame member 13, as shown in Fig. 2, having 100 a clasp 8, so that the upper end of this outer flap is securely closed and protected.

Secured to the opposite side of the main inner bag section is the outer pliant pocket forming section 3, which forms a smaller 105 pocket, while adjacent this smaller pocket 3, are the pen and pencil pockets 4, shown in Fig. 1, the smaller pocket 3, being protected by means of the flap 9, which has its ends continued to form the end flaps 11, covering 110 the pen and pencil holding end pockets 4. The larger flap 9 is secured by means of the

clasp 10, while the smaller end flaps 11, are held in place by means of the clasp buttons 12, as is usual in hand bag construction.

In order to securely hold the main inner bag section as well as the outer pliant pocket forming sections, and the end sections 6, to the frame members 13, I provide two clamping frame members 14, which are secured to the inner face of the bag forming members 10 by means of suitable rivets. According to this construction, the main inner bag section as well as the end sections, and the outer pliant pocket forming sections, and also the flaps are securely clamped between the members 13 and 14.

It should be understood that these hand bags will be made in various sizes and that any suitable material may be used in connection with the bag sections as well as the flaps.

A bag constructed according to my invention is simple and inexpensive, and both durable and efficient in operation.

Having thus described my said invention, what I claim as new and desire to secure by United States Letters Patent is:—

As a new article of manufacture, the herein described hand bag comprising two pivotally connected frame members, a main inner bag section having plaited side and bottom portions, pliant outer pocket forming members secured to the main inner bag section on opposite sides thereof, flaps covering the mouths of the outer pocket members, and clamping plates applied to the respective frame members, the said clamping plates serving to secure the edges of the inner bag section, the outer pocket members, and the flaps to the frame members.

In testimony whereof I affix my signature, in presence of two witnesses.

JOHN THENSER.
